UNITED STATES PATENT OFFICE.

LOUIS C. WITKOWSKI, OF WASHINGTON, DISTRICT OF COLUMBIA.

MERCHANDISE-CARRYING POST-CARD.

1,058,830.

Specification of Letters Patent. Patented Apr. 15, 1913.

Application filed November 18, 1910. Serial No. 593,116.

To all whom it may concern:

Be it known that I, Louis C. Witkowski, a citizen of the United States, residing at Washington, in the District of Columbia, 5 have invented certain new and useful Improvements in Merchandise-Carrying Post-Cards; and I do hereby declare the following to be a full, clear, and exact description of the invention, such as will enable others 10 skilled in the art to which it appertains to make and use the same.

This invention relates to improvements in mailing cards, and has for an object the arrangement of a card formed with means for 15 retaining a box on a card.

Another object of the invention is the arrangement of a mailing card arranged with means for holding a box on the card, and a flap having a retaining tongue for providing 20 an address space and an advertising space in proximity to the box carried by the card.

A further object of the invention is the arrangement of a mailing card formed with a plurality of retaining tongues, and an 25 address flap formed with a retaining tongue and one or more bracing tongues designed to hold a box from being accidentally moved off of the retaining tongues when the flap is folded.

30 A still further object of the invention is the arrangement of a mailing card with various means formed from a piece of suitable material designed to receive various kinds of boxes, and hold the same on the 35 card, the box being not only held on the card but prevented from opening while in transit, these box retaining means being associated with a flap which, together with one surface of the card proper, presents ample 40 advertising space at a proper position for attracting the eye when inspecting the box.

With these and other objects in view the invention comprises certain novel constructions, combinations, and arrangement of 45 parts as will be hereinafter more fully described and claimed.

In the accompanying drawings: Figure 1 discloses a blank embodying the invention. Fig. 2 is a front view of the invention with 50 the box applied, the card being shown folded and ready for mailing. Fig. 3 is a section through Fig. 2 on line 3—3. Fig. 4 is a plan view of a slightly modified form of card from that shown in Fig. 1. Fig. 5 is a view 55 similar to Fig. 1, showing a slightly modi-

fied form of the invention. Fig. 6 is a plan view of the blank shown in Fig. 5 folded ready for mailing, and provided with a package or box. Fig. 7 is a section through Fig. 6 on line 7—7. Fig. 8 is a view of a 60 blank disclosing a slightly modified form of the invention. Fig. 9 is a view of the structure shown in Fig. 8 folded and ready for mailing. Fig. 10 is a section through Fig. 9 on line 10—10.

65 In constructing a mailing card embodying the invention the same may be made of any kind of material, preferably some good quality of pasteboard or cardboard, and is arranged so that the same may be stamped out from a piece of material by a single operation of a tool. In stamping or cutting out the card the same is formed with what might be termed a base member and a flap member, each of said members being also formed with 70 tongues of various kinds for holding a box on the card, and for holding the flap in a folded position. The box may be formed either integral with the card or separate 75 therefrom, but in either instance the retaining tongues will hold the box in the particular place designed on the card.

80 In order that the invention may be more clearly understood an embodiment of the same is shown in the accompanying drawings, in which—

85 Fig. 1 indicates a base, and 2 a flap formed integral therewith designed to be folded over so that a retaining tongue 3 may project between the supporting tongues or box engaging members 4 and 5. When the flap 2 is folded over, as shown in Fig. 2, the tongue 3 is passed beneath the box mounted on members 4 and 5, so that the flap is held folded, and discloses the stamp and address. 90 In the structure shown in Figs. 1, 2 and 3 the box 6 is mounted on the right end of the card and a stamp on the upper left hand corner. However, these may be reversed if desired, so that the stamp may come at the usual place, and box 6 on or near the left end of the card, or at some other desired place according to the location of the box supporting tongues 4 and 5. Tongues or members 4 and 5 are cut as shown in Fig. 1 95 and designed to be bent at the scoring 7 and 8 so as to project into the housing 9 (Fig. 3) of box 6 for retaining the box in place. A bracing strip 5' is left between the tongues 4 and 5 so as to prevent the box from being 100 105 110

forced through the card. Box 6 may be of any desired structure of appropriate size, that shown for the purpose of illustration being a box having a casing 9 and a sliding receptacle 10. The box is applied to the card by sliding the same over one of the members 4 and 5, so that the said member will pass beneath the casing and the bottom of the receptacle 10. After this has taken place the other tongue is bent slightly and forced between the casing 9 and the bottom of receptacle 10. This may be easily done by sliding the receptacle 10 partially out of the casing 9, and then folding the tongue over into the housing 9, after which the receptacle is forced back to its original position. The tongues or members 4 and 5 usually provide sufficient friction for holding the receptacle 10 properly in housing 9, as well as holding the entire box in place, but to positively prevent the receptacle 10 from sliding out retaining tongues 11 and 12 are formed on flap 2. These retaining tongues 11 and 12 may be of course easily torn off or bent out of the way when it is desired to open the box for inspection, or for any other purpose. If the box 6 is made without the sliding receptacle 10, but having merely folding end closures, the tongues 4 and 5 will firmly hold the box in place without the assistance of tongues 11 and 12.

In Fig. 4 will be seen a slight modification of the showing in Fig. 1 wherein the flap 2 has a retaining tongue 14 provided with a projecting portion 15 which is designed to pass under or in box 6 when the tongue 2 is folded as shown in dotted lines.

In Figs. 5 to 7 inclusive is disclosed another slightly modified form of the invention from that shown in Fig. 1, in which the base member 1 is provided with box supporting tongues or members 16 and 17 which are scored at 18, 19, 20 and 21. The tongues 16 and 17 are bent first so as to extend at right angles to the plane of base member 1, and the outer end thereof is bent parallel so as to take the position shown in Fig. 7 when a box is placed on the card. This form of mailing card is provided not only with retaining tongues 11 and 12 but with bracing portions 13 and 13' extending substantially at right angles to the general direction of tongues 11 and 12. Preferably the members 13 and 13' are used with the form shown in Fig. 5, though if desired the same may be used with the form shown in Fig. 1. In either form of card the box 6 is held on the card firmly, and the contents are prevented from moving out of the box. It will also be observed that the box is held so as to open on the sides of the card, the box 6 shown being a rectangular box with the ends opened, and consequently the box extends transversely of the card with the open ends near each side of the card.

In Figs. 8 to 10 inclusive is disclosed a further slightly modified form of the invention in which is disclosed a mailing card or merchandise carrying post-card formed integral with a box positioned thereon. The base 1 is provided with a line of scoring 22 so that the box proper 23 may be properly positioned for engaging the tongues or box supporting members 4 and 5 after the box has been folded over and moved against the face of base 1. It will be observed that in this form the box extends transversely of the card and the ends of the box opened near each edge of the card. The box 23 is shown as formed integral with base 1, constructed similar to base 1 of Fig. 1, but it will be evident that the tongues 4 and 5 may be made longer and scored as shown in Fig. 5, in order that the tongues may engage the upper part of the box rather than the bottom. The box 23, as well as box 6, may be positioned on the base 1 according to the location of the box supporting tongues. In order to properly position box 23 base 1 must be provided with a turned over portion 24 in order to position the box back from the end of the card, the desired distance for causing the tongues 4 and 5 to properly engage the same. It will also be observed that in the forms shown in Figs. 1 and 5 a plurality of tongues are provided on the flap 2 so as to engage the box at three different points, the center tongue passing beneath the box for primarily holding the flap 2 in place, but incidentally bracing the box and the two side tongue constructions bracing and holding the box properly in position, and the contents against accidental removal. When the box is provided with a sealing strip the same assists in holding the box in proper place on the card, and insures the box against being opened by unauthorized persons, as such opening can not be accomplished without injuring the box or the sealing strip.

What I claim is:

1. In a merchandise carrying post-card, a base, a pair of tongues pressed out of said base extending toward each other for receiving and holding a box on said base, a flap arranged to fold over against said base, means projecting from said flap for holding the same in a folded position, and means projecting from said flap for preventing longitudinal movement of said box. 115
2. In a merchandise carrying post-card, a base formed with a pair of box retaining tongues projecting toward each other designed to project into the box and hold the same on said base, a flap extending from said base, and a tongue connected with said flap designed to extend beneath the box held in place by said box retaining tongues when said flap is folded. 125
3. In a merchandise carrying post-card, a 130

base, a flap extending therefrom and when unfolded presenting advertising space, box retaining tongues projecting from said base in proximity to the advertising space, a flap 5 retaining tongue extending from said flap and adapted to be positioned between said box retaining tongues when the flap is folded, and box bracing tongues extending from said flap for preventing longitudinal move-

ment of a box positioned on said retaining 10 tongues.

In testimony whereof I affix my signature in presence of two witnesses.

LOUIS C. WITKOWSKI.
